3 Claims. (Cl. 219—11)

1

This invention relates to the heat-treating of metal and particularly to the continuous electrical heating of metal strip.

Various methods and apparatus have been described heretofore for heating metal strip, particularly in the form of wire, by passing an electric current through the strip, the heating being effected by the resistance of the strip to the electric current. In such resistance-type furnaces, the electric current has been supplied to the strip either by induction or by means of contact members, usually in the form of brushes, which are subject to wear and have the disadvantage, among others, that they must be replaced frequently. Likewise, such prior heating furnaces have for the most part the disadvantage that they are not adapted for the heating of wide metal strip, and particularly metal strip of high electrical conductivity such as copper and its alloys.

It is therefore an object of this invention to provide improved means for continuously heating wide metal strip of high electrical conductivity.

Another object of this invention is to provide improved means for heating a moving metal strip.

Another object of the invention is to provide a furnace for continuously heating flat metal strip having the advantages obtained by electrical induction heating and free of the disadvantages attending prior resistance-type furnaces.

Other objects and advantages will become apparent from the following detail description and accompanying drawing, in which

Figure 1 is a plan view of an electric furnace illustrating one embodiment of this invention, and

Figure 2 is a side view, partly in section, of same, and

Figure 3 is a sectional view of a strip contact roll illustrating one embodiment of the invention, and

Figure 4 is a diagrammatic view of an electrical contact assembly illustrating another embodiment of the invention.

In accordance with this invention a novel process and apparatus are provided in which fluid conductors connected to a source of electromotive force supply an electric current through contact rolls to a moving strip of the metal to be heated. The moving strip is advanced lengthwise in a path designed to maintain the strip in contact with the rolls and the rolls are maintained in electrical contact with the fluid conductor, which, for instance, may be any suitable molten metal or liquid such as any suitable electrolyte or Wood's metal or mercury. The elec-

2

tromotive force may be obtained from any suitable source, although in the preferred form of the invention, a transformer with a single turn secondary is employed.

Referring to the drawing, in one embodiment of the invention, the strip 1 of the metal to be heated is advanced lengthwise horizontally through the furnace over contact rolls 2 and 3. In order to insure good electrical contact between the strip 1 and rolls 2 and 3, the strip is brought into contact with a substantial proportion of the roll surface by first passing the strip over roll 4 around rolls 2 and 3 and over roll 5.

In the preferred form of the invention, a transformer having a laminated core 11, and a primary coil 12 with leads 13 is employed as the source of electromotive force for passing a current through the strip. The secondary of the transformer is a single loop comprising a stationary metal bar or plate 10, liquid metal contacts 6, 7, 8 and 9, metal contact rolls 2 and 3 and the moving metal strip 1 between the contact rolls 2 and 3 all of which are insulated from the supporting framework. The bar or plate 10 partially encircles the primary 12 and is connected at one end to the liquid contacts 6 and 8 and at the other end to liquid contacts 7 and 9. Liquid contacts 6 and 8 are in contact with each end of contact roll 2 through axle 26 and liquid contacts 7 and 9 are in contact with each end of contact roll 3 through axle 27. A complete electric circuit is thus provided for the current induced from the primary 12, the current flowing through the plate or bar 10, the liquid contacts, the contact rolls and the moving strip 1 intermediate the contact rolls. By thus making the strip 1 a composite part of the secondary loop of the transformer, one of the chief advantages of electric induction heating is obtained, namely a current of very high amperage and relatively low voltage may be passed through the strip without having to resort to any expensive leads to the liquid conductors or special sources of electric power, the usual 220 volt or 440 volt 60 cycle power lines ordinarily available being entirely satisfactory for the input to the primary.

One form of contact roll, at 2 and 3 of Figures 1 and 2, embodying this invention is illustrated in detail in Figures 3 and 4. The portion of the roll contacting the metal strip 1 is shown at 31 with metal axle 33 and cup-like metal flanges 32. The flanges 32 are partially submerged in the liquid contacts 35 which liquid 35 is contained in a metal box 34 joined to plate 10. Good electrical contact is thus provided between the plate 10 and strip 1 through roll 31, axle 33, flange 32, liquid

35 and box 34. In the embodiment illustrated in Figures 1 and 2 such a liquid contact assembly is provided at each end of the contact rolls 2 and 3. In practice, it is usually desirable to provide the box 34 containing the liquid conductor, such as mercury, with a cover for instance as illustrated in Figures 1 and 2 at 28. Axle 33 and the portion 31 of the roll may be made hollow, so as to provide passage for any suitable temperature controlling medium. For instance, if desired, the contact 10 rolls can be cooled by passing water through the hollow portion.

In operation, the strip 1 may be passed through the furnace as a continuous length, for instance by stitching the ends of successive coils together, 15 or the strip may be handled in the form of individual coils. As illustrated in the drawing, a coil of the metal to be heated may be unwound from a reel 14 on the charge side of the furnace and wound up on a reel 36 on the discharge side of the furnace. Any suitable type of reel may be employed, for instance any of the well known expansible-core types 36, Figure 2, the expansion of the core and consequent gripping of the metal coil being effected for instance by operation of an air cylinder 15 with piston shaft 16.

As the strip 1 enters the furnace and leaves contact roll 2, it becomes progressively hotter as it advances toward contact roll 3 on the discharge end of the furnace, the temperature being increased with the increased time of passage of the current through the strip. The strip may be cooled after it leaves contact roll 3 or, in order to prevent the strip while hot, and in some instances soft, from coming in contact with contact roll 3 and being scratched thereby or otherwise deformed, a quench pipe 24 may be employed to cool the strip just before it reaches contact roll 3. For instance, water or wet steam or other cooling medium, depending upon the speed of cooling necessary to give the desired physical properties of the metal may be injected through pipe 24 and sprayed on the surface of the strip 1.

When it is desired to bright anneal or otherwise heat metal strip in a controlled atmosphere this may be accomplished by enclosing the strip 1 between rolls 2 and 3 in a housing 29, which is provided at each end with openings permitting passage of the strip through the housing. For instance, when brass is annealed wet steam may be injected through pipe 24 on the hot strip 1 to cool the strip and the resulting superheated steam drives out the air and fills the housing 29. Likewise, depending on its temperature, the superheated steam may tend to preheat the relatively cool strip entering the housing 29 from contact roll 2 and thus effect a saving in heat. The cooling medium, inert atmosphere and the like may be discharged from the housing 29 through any suitable outlet 30.

When the strip 1 is heated to relatively high temperature, any appreciable tension on the strip, for instance brought about in advancing the strip through the furnace, may result in some change in dimension of the strip, for instance a thinning of the strip due to stretching. This may be avoided by employing some suitable means for controlling the tension on the strip. For instance pinch rolls 23 adjacent the contact roll 3 and similar pinch rolls 38 adjacent the contact roll 2, both having an adjustable screw-down 25 for regulating the clearance of the rolls, may be operated in conjunction with the strip advancing means to control or prevent tension on the strip between rolls 2 and 3.

For instance on the discharge side of the furnace, a motor 20 may be employed to drive the reel 36 acting through a suitable gear-train enclosed in box 22 and motor 19 acting through a suitable gear-train enclosed in box 37 may be employed as a drag generator, in the usual manner, operating with a dynamic braking action on pinch rolls 23. Tension is thus provided on the strip 1 as it passes around contact roll 3 and a good electrical connection is thus provided between the roll and strip. Similarly on the charge side of the furnace, motor 18 acting through any suitable gear-train enclosed in box 38 may be employed to drive pinch rolls 38 which then cause the strip 1 to unwind from the coil supported by reel 14, and motor 17 acting through any suitable gear-train enclosed in box 21 may be employed as a drag generator, in the usual manner, having a dynamic braking action on reel 14. Tension on the strip 1 between pinch rolls 38 and reel 14 is thus provided so that a good electrical connection between the strip and contact roll 2 is obtained.

By employing such means for advancing the strip through the furnace, it is possible to prevent any tension, or to provide any desired tension, on the strip 1 between contact rolls 2 and 3. For instance, the speed of motor 20 which drives reel 36 may be set to provide the desired velocity of strip through the furnace. The speed of motor 18 which drives the pinch rolls 38 may then be so adjusted, for instance by any suitable automatic regulator, as to provide the desired tension or slack in the strip 1 between the pinch rolls 23 and 38. The motors 17 and 19, employed as drag generators, may likewise be provided with any of the well known automatic regulators for adjusting their field input to provide a constant tension in the strip as it passes over contact rolls 2 and 3. The usual manner of operating such motors as 17 or 19 to obtain a dynamic braking action is accomplished, for example with motor 19, by supplying less power to motor 19 than is required to cause pinch rolls 23 to advance the strip as rapidly as it is being advanced by reel 36. The strip 1 passing through pinch rolls 23 instead of being driven by them therefore actually turns them faster than they are being driven by motor 19. The motor 19 is consequently 50 driven by rolls 23 as a generator offering resistance to the turning of pinch rolls 23 and putting tension on the strip between the rolls 23 and reel 36.

The furnace of this invention may be employed 55 to heat metal strip of either high or low conductivity for instance in an annealing operation or in any other operation in which it is desired to continuously heat metal in strip form and any suitable source of electromotive force may be applied to the fluid conductors. In the preferred embodiment described above an alternating current, which may be of either high or low frequency, or, for instance, any of the available standard commercial frequencies, is applied to the primary leads 13 and the strip is heated by the current induced in the secondary loop. The primary may be composed of a coil 12 with a laminated iron core 11, or may consist of a coreless primary coil, or may consist of a primary coil wound about a leg of the core outside the secondary loop.

The temperature to which the strip is heated may be controlled either by the power input to the fluid conductors or by the speed of travel of the strip; that is, the higher the power input,

or the slower the speed of travel of the strip, the higher the temperature of the strip. For instance, employing a furnace designed in accordance with the preferred embodiment described above, yellow brass strip about 15 inches wide and 0.006 inch thick may be passed through the furnace at the rate of about 27 feet per minute with a power input into primary 12 of about 31 kilowatts per hour to yield about 540 pounds of brass strip per hour heated to about 700° C.

If it is desired to pickle the strip after it is heated, this may be accomplished by passing the strip through a suitable pickling bath as it leaves the furnace.

If it is desired to heat more than one strand of metal at a time, this may be readily accomplished in accordance with this invention, for instance by providing contact rolls for each of such strands and so connecting the liquid conductors accompanying the contact rolls that the moving strands are electrically connected in series, or parallel as desired, with respect to the source of electromotive force. Similarly, more than one strand of the metal may be heated by simultaneously passing a plurality of strands over contact rolls, either with one on top the other, for example in forming laminated sheet and the like or, for instance with narrow strands, side by side in parallel paths. The word "strip," therefore, is used in describing the invention herein and in the claims in a sense inclusive of one or more strands of the metal to be heated.

This invention accordingly provides means for the economical continuous heat treating of magnetic or non-magnetic metal strip of either high or low electrical conductivity in the form of flat strip having any desired width, wire, or the like and has a wide field of utility without being subject to all the limitations and disadvantages obtained with prior processes and apparatus.

It is to be understood that the embodiments of the present invention as shown and described are only illustrative, and that many changes may be made therein without departing from the spirit and scope of the invention as set forth in the following claims.

Having thus described the invention, what is claimed and desired to secure by Letters Patent is:

1. In an electric furnace for heating moving metal strip, the combination which comprises a plurality of spaced metal rolls for contacting said moving metal strip, one of said rolls being on the charge end and one on the discharge end of said

furnace, liquid electric conductors for supplying an electric current to said strip through said rolls, means for applying an electromotive force to said liquid conductors, means for providing tension on said strip as it passes over each of said rolls and means for providing a substantially lesser tension on said strip between said rolls.

2. In an electric furnace for heating moving metal strip, the combination which comprises a

10 plurality of spaced metal rolls for contacting said moving metal strip, liquid electric conductors for supplying an electric current to said strip through said rolls, means for applying an electromotive force to said liquid conductors to heat

15 said strip, motor drive means in front of each of said rolls for advancing the strip over said rolls and drag-generator means in back of each of said rolls for providing tension on said strip as it passes over each of said rolls, means between

20 said rolls for rapidly cooling said hot strip and a housing enclosing said strip between said rolls.

3. In an electric furnace for heating moving metal strip, the combination which comprises spaced metal rolls for contacting said moving

25 metal strip one of said rolls being on the charge end and one on the discharge end of said furnace, liquid electric conductors for supplying an electric current to said strip through said rolls, means for applying an electromotive force to said liquid conductors, motor drive means in front of each of said rolls for advancing the strip over said rolls and drag-generator means in back of each of said rolls for providing tension on said strip as it passes over each of said rolls.
